Primary Examiner—Catherine E. Kemper

[57] CLAIM

The ornamental design for a barbecue, as shown and described.

DESCRIPTION

FIG. 1 is an isometric view of a barbecue showing my new design.

FIG. 2 is a rear elevational view thereof.

FIG. 3 is a front elevational view thereof.

FIG. 4 is a top plan view thereof.

The support post has been shown fragmentarily in FIGS. 1-3 to indicate indeterminate length.
